United States Patent Office.

JONATHAN DAVISON, OF PLYMOUTH, MICHIGAN.

Letters Patent No. 66,806, dated July 2, 1867.

CHURN.

The Schedule referred to in these Letters Patent and making part of the same.

TO ALL WHOM IT MAY CONCERN:

Be it known that I, JONATHAN DAVISON, of Plymouth, in the county of Wayne, and in the State of Michigan, have invented certain new and useful improvements in Churns; and do hereby declare that the following is a full, clear, and exact description thereof, reference being had to the accompanying drawings, and to the letters of reference marked thereon.

In the annexed drawings, making part of this specification, A represents an ordinary barrel or cylinder churn, which is provided with a cover, C. This cover is provided with a hole or opening to receive the dasher-staff D, and this hole or opening is provided with a slot, e, to receive the tube a of the dasher-staff. D represents the dasher-staff, which is provided with a long spiral tube, a, which runs in the groove e, and which serves to give the staff D a rotary motion independent of its reciprocating motion, and allows air to pass into the churn. Upon the lower end of the staff D is secured the dasher J J', which is made double, the upper one, J, being composed of two strips, which are placed at right angles to each other, and perforated or notched as may be desirable, and secured to the lower end of the staff. The dasher, or part of the dasher, J', is constructed similarly to the part J, but is placed a little below it, being connected to it by means of the rods i i. The shaft D is given a reciprocating motion by means of a lever-handle, F, to which it is connected at its upper end. The lever F has its fulcrum in or upon a support, G, which is attached at its lower end to the churn body, and passes through, and is kept in place by means of a projecting arm, H. That end of the lever F to which the staff D is attached is provided with a slot, and in this slot is pivoted a swivel-block through which the upper end of the staff passes, and in which it is secured. The staff D is given a reciprocating or vertical motion, and at the same time a rotary motion, by means of the lever F. The upper end of the staff revolves in the swivel-block, as it (the staff) is caused to revolve by the thread a working in the slot e of the opening in the churn cover.

Having thus fully described my invention, what I claim as new, and desire to secure by Letters Patent, is—

The arrangement of the staff D, provided with its tube a and dashers, with the churn body and the lever F, provided with its swivel-block, for the purpose of churning milk or cream, substantially as herein specified.

In testimony that I claim the foregoing I have hereunto set my hand this 22d day of April, 1867.

JONATHAN DAVISON.
